UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,858**, dated September 2, 1873; application filed August 9, 1873.
[Term of Patent 3½ years.]

K.

To all whom it may concern:

Be it known that I, FREDERICK WINK, of Philadelphia, Pennsylvania, have invented a Design for a Shawl-Pattern, of which the following is a specification:

The figure in the accompanying drawing fully represents my design for a shawl-pattern, the main features of which are the wide and narrow stripes A and B.

The central ornament *a* of the stripe A is ornamented by diamonds, angular ribs, short transverse and straight parallel ribs, all arranged in a manner so clearly shown in the drawing as to require no minute description. The said stripe A is further ornamented by shaded parallel bars or ribs and rows of dots or dashes, arranged in couples, as shown. The

stripe B is composed of a series of minor parallel stripes, and has near each edge a bar composed of diamonds, dots, and short transverse ribs, arranged as illustrated.

Irrespective of the colors employed, I claim—

1. The design for the stripe A, as shown and described.
  2. The design for the stripe B, as described and represented.
  3. The design for the whole pattern, including the stripes A and B.

In testimony whereof I have signed my name to this specification in the presence of two subscribing witnesses.

Witnesses: FRED. WINK.
CLINTON M. LATOURETTE,
LEWIS T. GODFREY.
